(57) **CLAIM**

The ornamental design for a shopping cart, as shown and described.

DESCRIPTION

FIG. 1 is a perspective view of a shopping cart showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is another perspective view thereof;

FIG. 9 is a front view of a shopping cart with the door open to the right;

FIG. 10 is a front view with the door open to the left;

FIG. 11 is a front view with the door and cart separated;

FIG. 12 is an enlarged portion of the left buckle taken from line 12 in FIG. 2;

FIG. 13 is an enlarged portion of the left wheel taken from line 13 in FIG. 2;

FIG. 14 is an enlarged portion of the right buckle taken from line 14 in FIG. 3;

FIG. 15 is an enlarged portion of the right wheel taken from line 15 in FIG. 3;

FIG. 16 is an enlarged top plan view of the left wheel;

FIG. 17 is an enlarged top plan view of the left button;

FIG. 18 is an enlarged bottom plan view of the left wheel; and,

FIG. 19 is an enlarged bottom plan view of the right wheel.

The broken lines shown in the drawings show enlarged portions of the shopping cart and form no part of the claimed design.

1 Claim, 19 Drawing Sheets
